(57) **CLAIM**

The ornamental design for a scalloped hopper wind screen, as is shown and described herein.

DESCRIPTION

FIG. 1 is a perspective view thereof;

FIG. 2 is a rear elevational view thereof;

FIG. 3 is a top elevational view thereof;

FIG. 4 is a bottom elevational view;

FIG. 5 is a front side elevational view thereof; and,

FIG. 6 is a left side elevational view thereof; the right side elevational view being a mirror image thereof.

The dotted lines show environment only and are not a claimed portion of the design.
